UNITED STATES PATENT OFFICE.

GEORGE C. FATSCHER, OF NEW HAVEN, CONNECTICUT, ASSIGNOR TO THE NEW HAVEN SAND BLAST COMPANY, OF NEW HAVEN, CONNECTICUT, A CORPORATION OF CONNECTICUT.

SAND-BLAST APPARATUS.

Application filed July 10, 1923. Serial No. 650,659.

My invention relates to sand blast apparatus, and particularly to the mixing chamber at which sand is taken up by the blast, as for instance in a sand blast hose machine. The 5 object of my invention is to provide a mixing chamber of such construction that an even, free and well distributed supply of sand to the blast is insured during the operation of the apparatus, while clogging of 10 the chamber by sand on halt of the blast is prevented. A further object of the invention is to provide a construction in which parts most subject to wear are readily accessible for renewal.

15 In the accompanying drawings:—

Fig. 1 is a vertical section through a mixing chamber in which my invention is embodied in one form; and

20 Fig. 2 is a section on the line 2—2, Fig. 1. In certain prior constructions, such for example as that shown in the Dreisbach Patent No. 1,093,551, April 14, 1914, attempt has been made to provide for the proper 25 delivery of the sand to the blast which passes through the mixing chamber, and to prevent clogging of the latter when the blast is halted. Experience has proven, however, that sand is not readily taken up by the blast from the bottom of a chamber 30 such as that shown in the Dreisbach patent, while moist sand will not freely flow to a mixing chamber through the lateral apertures such as are there provided for the purpose. The present construction obviates 35 these difficulties by insuring the delivery of the sand in suspension to the blast, and providing, furthermore, suitable means below the sand feed aperture which prevents the complete closure of the blast passage by the sand when the blast is halted.

40 In the illustrative embodiment of my invention shown in the accompanying drawings, the sand hopper or storage tank 1 delivers to the throat 2 at the top of the mixing chamber casting 3. To one end of the chamber 4 of the latter air enters by the air blast pipe 5, while at the opposite end of the chamber is the outlet fitting 6 through which the entrained sand passes to the point of use. A blast hose (not shown) is commonly connected to the fitting 6. Any suitable means, such as screw bolts 7, connect the fitting 6 detachably to the casting 3.

Held within the chamber 4 by the fitting

6 is a renewable lining sleeve 8 having a 55 feed port 9 in register with the hopper throat 2. Spaced beneath the port 9 is a feed plate 10, preferably arranged substantially on the horizontal diameter of the sleeve 8. The feed plate 10 is preferably independent of the sleeve 8 and is accommodated in longitudinally extending channels 11 formed in the inner face thereof. Any suitable means may be provided for properly positioning the sleeve within the chamber 4 in order to insure registry of the port 9 with the delivery throat 2 and the horizontal position of the feed plate 10. For 60 this purpose I have shown bosses 12 on the sleeve adapted to enter between guide ribs 13 on the inner wall of the chamber 4. Studs 14 arranged at appropriate points on the inner wall of the chamber, engage the sleeve 8 and properly position the latter. An inner shoulder 3^a on the casting 3 forms 65 an abutment for one end of the tubular lining 8, while the opposite end of the lining is engaged by the inner margin of the outlet fitting 6. The lining is thus secured accurately in position not only by the bosses 12 and ribs 13 against rotation in the chamber, but also by the shoulder 3^a and outlet fitting 6 against longitudinal displacement.

70 To control the amount of sand delivered to the mixing chamber, I provide a gate valve 15 at the inner end of a slide rod 16, which valve works in the throat 2 above the port 9 in the sleeve 8. By moving the rod in the direction of its length, the port is 75 80 accurately uncovered.

85 The direction of the air blast is indicated by the arrow X, and it will be noted that the port 9 in the sleeve 8 is inclined in the direction of the flow of the air blast through the mixing chamber.

90 When the apparatus is in operation, the sand passing down through the throat 2 and port 9 falls into the blast entering through the pipe 5. Such sand as is not picked up and carried along by the blast in suspension, falls upon the feed plate 10 and is 95 100 propelled by the air beyond the edge of the plate, where it is delivered into that portion of the blast which passes beneath the feed plate 10, and is taken up and carried 105 along in suspension thereby. The inclination of the port 9 in the direction of the air current assists the feed of the sand from the

throat to the mixing chamber, since the blast flowing past the mouth of the port exerts a suction effort on the sand feed. The sand feed may be regulated or entirely cut off by 5 operating the gate 15. Should the air blast be halted while the gate is in open position, the flow of sand into the mixing chamber continues until a cone 17 is built up, which automatically closes the port 9 and substantially 10 chokes the upper portion of the mixing chamber, above the feed plate 10. The passageway 18 below the feed plate however, is maintained open, and upon the renewal of the blast the air flows with increased 15 velocity through the lower passageway 18. If the air pressure is not sufficient to dislodge the cone 17 at once, it is gradually broken down by reason of eddy currents or the vacuum created at A by the flow of air through the lower portion 18 of the passage, and its expansion beyond the feed plate. The sand is dislodged from one face 20 of the cone and drawn over the delivery edge of the feed plate 10. As soon as the cone 25 is sufficiently broken down to open air passages along the sides thereof, the sweep of the blast therethrough rapidly breaks down the remainder of the cone and renews the normal operation of the apparatus. While 30 the feed plate 10 thus performs the important function of preventing the clogging of the mixing chamber, it also performs the important function of preventing the sand from falling directly across the feed chamber 35 when the apparatus is in operation. As above stated, such sand as is not taken up by the portion of the blast which flows above the feed plate is forced along the latter and discharged in the direction of the flow of 40 the blast to that portion of the latter which passes beneath the feed plate. The sand is distributed in a relatively thin layer, and leaves the feed plate substantially horizontally and in the direction of the flow of 45 the blast, so that it is readily taken up and carried along in suspension by the portion of the blast which emerges from beneath the feed plate.

I have found that even moist sand will 50 readily feed through a mixing chamber of the present construction without any tendency to clog, either at the port 9 or elsewhere, and that even when the blast is halted with the port open and a wet cone 18 is 55 built up on the feed plate 10, the action of the blast breaks down the cone and renews the feed with almost as great celerity as in the case of perfectly dry sand. I have found, furthermore, that an apparatus of 60 substantially the same dimensions, and operated with a blast of the same pressure,

takes up and delivers a far greater quantity of sand in a given time than apparatus of the type illustrated in the patent above mentioned. The efficiency of the blast is therefore greatly increased. 65

Various modifications in detail of construction and arrangement of parts will readily occur to those skilled in the art which nevertheless embody the features 70 which I claim as my invention.

I claim:—

1. In sand blast apparatus, a mixing chamber having a readily removable lining subdivided by an independent, readily removable feed plate. 75

2. In sand blast apparatus, a mixing chamber having a readily removable lining subdivided by a feed plate, said lining being apertured to afford a feed port above the feed plate, said port being inclined in the direction of the flow of air through the mixing chamber. 80

3. In sand blast apparatus, a mixing chamber having a sand feed throat, a removable tubular lining arranged beneath said throat and ported for registry therewith, and fixed means for positively locating said lining in position to insure registry between said port and throat. 85

4. In sand blast apparatus, a mixing chamber having a sand feed throat, a removable tubular lining arranged beneath said throat and ported for registry therewith, and fixed means for positively locating said lining in position to insure registry between said port and throat, together with a feed plate subdividing said lining into upper and lower blast passages, said port being located to deliver sand to the upper blast passage in the lining. 90

5. In sand blast apparatus, a mixing chamber having a removable tubular lining ported in its upper wall to afford a sand feed opening to the interior of the lining, in combination with an independent feed plate horizontally sub-dividing the interior of the tubular lining and removable therefrom by displacement in the direction of the length of the tubular lining. 1

6. In sand blast apparatus, a mixing chamber, abutments of less diameter than the chamber at opposite ends thereof, a tubular lining for the chamber engaged between said abutments and having an opening in its upper wall to form a sand feed port, together with a feed plate horizontally sub-dividing said lining. 1

In testimony whereof I have signed my name to this specification.

GEORGE C. FATSCHER.
